CIRCUMFERENTIAL CYLINDER REGISTER
MECHANISM FOR ROTARY PRINTING
MACHINES

Max Ras, Zurich, Switzerland

Application December 28, 1949, Serial No. 135,424

Claims priority, application Switzerland

2 Claims. (Cl. 101—248)

1

My present invention relates, generally, to improvements in rotary rolling-contact printing machines and, in particular, to the circumferential cylinder registering mechanism thereof.

In offset machines, to which my present invention has special reference, the cylinders are driven through a pair of helical gear wheels, and the additional rotation of a cylinder required for circumferential cylinder registering is brought about through axially displacing one of said gear wheels.

When the driving gear wheels are rigidly connected to the appurtenant cylinders, which is of advantage from the standpoint of operation, some of said gear wheels and also the cylinders, blankets and plates have to be made of excessive width or length, since on adjusting the lateral cylinder register it may happen that the spur-gear driven plate cylinder has to be displaced toward one machine side, while the adjustment of the circumferential cylinder register, which in offset machines is done on the offset or rubber cylinder, may require a displacement toward the other machine side. Another adjusting device, which does not possess the said advantage, has a gear train intermediate of the cylinders, which train comprises two rim gears of different diameters and may operate as conventional or as epicyclic gear drive. By means of such latter gearing, the cylinder while rotating may be reset through a stationary adjusting mechanism. Such device, however, has the disadvantage that the entire force for driving the cylinders has to pass through these relatively small planet wheels which thus are given a comparatively high number of revolutions. The multiple tooth engagements may cause an increased backlash, which again may cause register differences.

In the mechanism according to my present invention, the displaceable helical gear wheel comprises a further lateral toothed rim which engages a rim provided with inside teeth, which latter rim is connected to the gear wheel keyed to the cylinder axle.

One form of my present invention is shown by way of example in the accompanying drawing, in which—

Fig. 1 shows schematically the cylinders of a rotary offset machine and its drive,

Fig. 2 is an axial section in larger scale through the drive mechanism for the rubber cylinder at the left end thereof, and

Fig. 3 is an axial section through the right end of the rubber cylinder, showing the means for adjusting the circumferential or cylinder register.

2

In Fig. 1, a plate or form cylinder 1, a rubber cylinder 2, and a counterpressure cylinder 3 are mounted in a machine frame 4. The cylinders are driven, e. g. by way of a pair of bevel gears 5, by means of a gear 6 having skewed or helical teeth, which gear is keyed to the shaft of the counterpressure cylinder 6 and engaged with an axially displaceable gear wheel 7 having skewed or helical teeth. A spur gear wheel 8 rigidly keyed to the axle of rubber cylinder 2 and meshing with gear wheel 7 by internal gear means drives a spur wheel 9. A handwheel 10 arranged on the machine side opposite to the drive gear, serves for adjusting the lateral register, and a second handwheel 11 serves for adjusting the circumferential register.

As shown in Fig. 2, the gear wheel 7 which is provided with skewed or helical teeth, is mounted axially displaceable on the extended hub 12 of spur wheel 8 and is provided on its side with an external gear 13 which meshes with an internal gear 14 of spur wheel 8 which is rigidly keyed to the cylinder axle 16. Drive is transmitted by way of the internal gears 13, 14 from gear wheel 7 onto the spur wheel 8.

For the purpose of axially displacing the helical gear wheel 7, in order to adjust the circumferential register, there is provided a rod 17 traversing the hollow cylinder axle 16. The rod 17 at one end is coupled to gear wheel 7 by means of a disc 18 and screws 19, and at the other end to an adjusting mechanism shown in section in Fig. 3 and actuated by means of handwheel 11.

The cylinder 1 is axially displaceable relatively to the machine frame 4 by means of handwheel 10 for lateral register, and such displacement does not affect the position of the cylinders 2 and 3 which are axially non-displaceable. Circumferential register of cylinder 1 with respect to cylinders 2 and 3 is brought about by turning handwheel 11 whereby the rod 17 and thus the gear wheel 7 is axially displaced. Gear wheel 7, being in mesh with the helical gear wheel 6, is rotated by virtue of its axial displacement with respect to the latter, and spur wheel 8 follows the rotation of gear wheel 7 and in turn rotates the spur wheel 9 so as to turn the cylinder 1 into circumferential register with the cylinders 2 and 3. It is to be noted that the gear wheels 7 and 9 are of lesser face width than the respective gear wheels 6 and 8 meshing therewith, and that also the intermeshing internal gears 13, 14 are of substantial width, and the wheels 7 and 8 thus may be axially displaced to quite some extent with respect to the wheels 6.

and 9 and still be in engagement therewith. It further is to be noted that the mechanism for axially displacing the cylinder 1 by means of handwheel 10 is similar to that shown in Fig. 3 for axially displacing the rod 17 and gear wheel 1.

The internal gearing 13, 14 has the advantage of a comparatively large diameter, which feature prevents any substantial backlash in the circumferential direction. The power is distributed onto all the teeth, and the resulting low tooth pressure allows a remarkably easy axial displacement of the internal gears 13, 14 relatively to each other.

What I claim as new and desire to secure by Letters Patent, is:

1. In a circumferential cylinder register mechanism for rotary printing machines in which the cylinder drive mechanism comprises a pair of helical gear wheels and a spur gear wheel rigidly keyed to the axle of a cylinder and having intermeshing gears between the spur gear and one of said helical gear wheels wherein the axial displacement of said latter helical gear wheel causes the additional rotation of a cylinder as required for circumferential cylinder register, the improvement consisting in incorporating an

extended hub on said spur gear wheel, said extended hub bearing the axially displaceable helical gear wheel, an external gear on the side of said helical gear wheel, and an internal gear on said spur gear wheel, meshing with said external gear for transmitting rotation of said axially displaceable helical gear wheel to said spur gear wheel.

2. In circumferential cylinder register mechanism as claimed in claim 1, a hollow cylinder axle for one said cylinder supporting said spur gear wheel, a rod inserted through said hollow axle, said rod at one end being connected to the said displaceable helical gear wheel and a manually actuatable adjusting mechanism connected to the other end thereof.

MAX RAS.
